Des. 229,636

Patented Dec. 18, 1973

229,636

CASING FOR A PEN OR THE LIKE

Eugene Defores, Nantes, France, assignor to
Societe Le Foyer, Paris, France

Filed Nov. 24, 1971, Ser. No. 202,050

Claims priority, application France May 25, 1971

Term of patent 14 years

Int. Cl. D19—06

U.S. Cl. D74—17 B

FIG. 1

FIG. 2

FIG. 3

FIG. 4

FIG. 5

FIG. 1 is a top plan view of a casing for a pen showing my new design,

FIG. 2 is a side elevational view thereof,

FIG. 3 is a front elevational view thereof,

FIG. 4 is a bottom plan view of FIG. 2, and

FIG. 5 is a partial sectional view, on an enlarged scale, taken along line 5—5 in FIG. 2.

I claim:

The ornamental design for a casing for a pen or the like, as shown.
